UNITED STATES PATENT OFFICE.

LOUIS C. HILLER, OF MERIDEN, CONNECTICUT.

DESIGN FOR A CLOCK-CASE.

SPECIFICATION forming part of Design No. 16,899, dated September 14, 1886.

Application filed August 4, 1886. Serial No. 210,022. Term of patent 7 years.

To all whom it may concern:

Be it known that I, LOUIS C. HILLER, a citizen of the United States, residing at Meriden, in the county of New Haven and State of Connecticut, have invented and produced a new and original Design for Clock-Cases; and I do declare the following to be a full, clear, and exact description of the same, reference being had to the accompanying drawing, forming a part thereof, which represents my improved design in front elevation.

The design consists of a clock-case representing the front of a locomotive and bearing a dial.

15 1 denotes a representation of the cab of a locomotive; 2, the steam-chests; 3, the cylin-

ders; 4, the pilot; 5, the head-light; 6, the smoke-stack, and 7 the dial, which occupies a position representing the front of the boiler.

Having thus described my invention, I claim—

The design for a clock-case, consisting of a representation of the front of a locomotive having a dial at the position representing the front of the boiler, substantially as shown. 25

In testimony whereof I affix my signature in presence of two witnesses.

LOUIS C. HILLER.

Witnesses:

LOUIS CASPER,
LEMOINE N. FAY.
